[57] CLAIM

The ornamental design for a automobile steering wheel lock, as shown and described.

DESCRIPTION

FIG. 1 is a top, front, and right end elevational view of an automobile steering wheel lock showing my new design;

FIG. 2 is a front elevational view thereof;

FIG. 3 is a rear elevational view thereof;

FIG. 4 is a left end elevational view thereof;

FIG. 5 is a right end elevational view thereof;

FIG. 6 is a top plan view thereof;

FIG. 7 is a bottom plan view thereof; and

FIG. 8 is a reduced top, front, and right side perspective view thereof, the broken-line disclosure of a fragments of an automobile being for illustrative purposes only and forming no part of the claimed design.

FIG. 1

FIG. 2

FIG. 3

FIG. 4**FIG. 5**FIG. 8
